DISPENSING DEVICE FOR SHEETS OF FLEXIBLE MATERIAL

Burke M. Baxter, Middletown, Ohio, assignor to
The Crystal Waxing Company, Middletown,
Ohio, a corporation of Ohio

Application March 25, 1932, Serial No. 601,237

7 Claims. (Cl. 206—57)

My invention relates to dispensing devices for sheets of flexible material such as waxed or tissue paper and the like and particularly to a novel container formed for use as a dispensing package.

It is the object of my invention to provide a container for a folded group of flexible sheets which container serves for retaining the sheets substantially flat for shipment but which may be opened out so as to provide a dispensing device which may be suspended from a support and which will hold the sheets in such form that they may be readily withdrawn.

Another object of my invention is to provide a dispensing carton which may be made from a single cut and scored blank and which blank will have a wall subdividing the fold line between the sheets of flexible material packaged within the container.

A further object of my invention is to provide a blank having an interlocking flap or tab which may be used for retaining the walls of the container together when the package of sheets is shipped but which upon withdrawal, may be utilized as a hanger by which the container may be suspended so that the sheets will be held in a position from which they may be easily withdrawn.

A still further object of my invention is to provide a package of sheets having an outer container holding the same which has a portion of a wall which may be folded down so that end edges of the sides of the sheets may be exposed in such position that they are readily grasped for withdrawing the sheets from the container.

The above objects and other objects to which reference will be made in the ensuing disclosure, I accomplish by that certain combination and arrangement of parts of which I have illustrated a preferred embodiment.

Referring to the drawings:

Figure 1 is a plan view of a preferred type of blank.

Figure 2 is a perspective view of the closed container ready for shipment.

Figure 3 is a perspective view of the container in dispensing position with edges of the sheets exposed to facilitate their easy withdrawal from the container.

The container has a front wall A having a portion B joined to the main body of the portion A by a line of articulation indicated at *a—a*. The portion B is provided with a slot C, the purpose of which will hereinafter be described.

Articulated to the portion A, there is a bottom wall portion D having a length corresponding to

the length of the portion A and a width which determines the width of the finished package.

Articulated to the bottom wall D at the end opposite that to which the wall D is joined to the front wall A, there is a back wall E.

Articulated to the back wall E, there is a top wall F of substantially half the width of the bottom wall D and articulated to the wall F is the stack subdividing wall G.

Cut from the top wall F and the tuck-in subdividing wall G is a cut-out tongue H having preferably two apertures I, J subdivided by a score line K.

In packaging the sheets such as are indicated in folded position at L, the operator takes a desired number of sheets, backs them in front of her on a table and places the blank so that the upper edge of the wall G extends down the medium line of the sheets. The uncovered edge of the sheets are then folded in so that the ends of the sheets lie substantially in alignment with the line of articulation between the top flap F and the divider flap G.

The flap G then together with the folded sheets are folded down over the back wall E. The front flap A is then folded up to overlie the exposed halves of the sheets, the other halves of which are retained between the flaps G and E. The side sealing flaps M are then folded around from the position shown in Figure 1 to the position shown in Figures 2 and 3 and the sealing tabs O, P, are secured with adhesive to the back surface of the back wall E.

The attaching tongue H is then folded over and the tip inserted within the slot C so that the front, back and subdividing walls of the carton will retain the folded sheets in flat condition.

When it is desired to open up the carton for dispensing, the interlocking tongue H is withdrawn from the slot and the tip of the tongue is folded back so that the aperture J registers with the aperture I. The tongue H then forms a hanger by which the carton may be suspended from a nail or hook.

The portion B is then folded down in the position shown in Figure 3 and the outwardly exposed sheet of the folded sheets may be withdrawn without tearing. It will be observed that as the sheets are withdrawn, the subdividing wall G keeps the sheets in stacked condition preventing the withdrawal of more than one sheet.

The container thus formed and filled with sheets finds a ready market as the container provides both a carton for holding the sheets in folded position and also provides a dispensing

package which will permit the withdrawal of the sheets, sheet by sheet, without likelihood of more than one sheet being drawn out at a time.

Having thus described my invention, what I claim as new and desire to secure by Letters Patent, is:—

1. A container for folded stacks of flexible sheets, said container formed from a cut and scored blank, and having a front wall substantially half the size of said sheets, a bottom wall, a back wall substantially one half the size of said sheets and a separating wall extendible within the fold of the stacks of sheets, said front wall having an articulated portion which may be bent outwardly to expose outside the body of said container, ends of said stacks to permit the separate withdrawal of the sheets of said stacks.

2. A container for folded stacks of flexible sheets, said container formed from a cut and scored blank, and having a front wall substantially half the size of said sheets, a bottom wall, a back wall substantially one half the size of said sheets and a separating wall extendible within the fold of the stacks of sheets, said front wall having an articulated portion which may be bent outwardly to expose outside the body of said container, the ends of said stacks to permit the separate withdrawal of the sheets of said stacks, said back wall and said front wall having interengaging means for holding the articulated portion of said front wall in position and thereby retaining the ends of said stacks within the body of said container.

3. A container for folded stacks of flexible sheets, said container formed from a cut and scored blank, and having a front wall substantially half the size of said sheets, a bottom wall, a back wall substantially one half the size of said sheets and a separating wall extendible within the fold of the stacks of sheets, said front wall having an articulated portion which may be bent outwardly to expose outside the body of said container, the ends of said stacks, to permit the separate withdrawal of the sheets of said stacks, said back wall and said front wall having interengaging means for holding the articulated por-

tion of said front wall in position and thereby retaining the ends of said stacks within the body of said container, said interengaging means comprising a tongue cut from said separating wall and articulated to said back wall, and said front wall having a slotted portion to receive said tongue.

4. A package of flexible sheets comprising retaining walls articulated together with one of said walls forming a divisional wall holding said sheets in a single medially folded stack, one of said walls being bendable outwardly to expose end edges of said sheets.

5. A package of flexible sheets comprising retaining walls articulated together with one of said walls forming a divisional wall holding said sheets in a single medially folded stack, one of said walls being bendable outwardly to expose end edges of said sheets, said divisional wall extending clear into the fold of said stack so as to bear against the medial line of the inner sheet of said stack to facilitate the withdrawal of sheets one by one.

6. A package comprising a container and a stack of flexible sheets retained in an upright medial fold within said container, said container having an integral wall of half the size of said sheets inserted within the fold of said sheets to act as a retarding device to facilitate the withdrawal of sheets, said container having an integrally formed wall bendable outwardly to expose edges of said folded stack, and a locking tab for normally retaining said bendable wall in flat position.

7. A container for flexible sheets provided with enclosing walls of substantially half the size of said sheets and having means for retaining a stack of flexible sheets in an upright medial fold, said means further acting as a retarding device to facilitate the withdrawal of sheets singly, said enclosing walls being provided with an articulated flap bendable to expose edges of a stack of sheets retained thereby, and said walls having a cut out tongue for retaining said articulated flap in alignment with said enclosing walls.
